UNITED STATES PATENT OFFICE.

WILLIAM T. VAN DORN, OF CHICAGO, ILLINOIS.

RAILWAY-COUPING.

1,121,692.

Specification of Letters Patent. Patented Dec. 22, 1914.

Application filed May 10, 1909. Serial No. 495,039.

To all whom it may concern:

Be it known that I, WILLIAM T. VAN DORN, a citizen of the United States, and a resident of the city of Chicago, in the county of Cook and State of Illinois, have invented certain new and useful Improvements in Railway-Couplers; and I do hereby declare that the following is a full, clear, and exact description of the same, reference being had to the accompanying drawings, and to the letters of reference marked thereon, which form a part of this specification.

With the recent very great extension of interurban electric lines, (many of which are engaged in inter-state commerce) the necessity has arisen for bringing the draft equipment of the rolling stock for such roads into conformity with the Federal law. In consequence, and furthermore because of the necessity sometimes arising for such roads to handle cars taken from steam roads, it follows that some type of M. C. B. coupler or at least a coupler or drawhead capable of coupling with the M. C. B. drawheads used on steam roads be employed. When employed on such roads, however, the conditions are quite different than when employed on steam roads for the reason that inasmuch as such interurban or electric roads usually contain many more and much shorter curves than steam roads, it has become the practice (and may be considered a necessity for the draft gear of such cars as are used in interurban service) to provide for considerable lateral movement of the drawhead to enable the cars to pass around such curves.

With steam roads, the conditions, though different, are sufficiently similar to frequently cause breakage of drawheads or knuckles on curves. It therefore follows that whatsoever type of drawhead is employed for interurban service, the drawheads should engage so rigidly together as to afford but little lateral movement of one drawhead relatively the other when coupled, and also to so rigidly engage together as to enable the draft gear of the drawheads of the two coupled cars to remain substantially in alinement (if both are free) to swing or adapt themselves to the curves in the track. Where this is not the case, breakage of parts is almost inevitable and consequent danger, loss and delay.

A further objection to drawheads and couplers as heretofore constructed is that the

knuckles are permitted to continually move laterally of each other when coupled causing excessive wear at the ends thereof and also the continual friction between the meeting faces of the knuckles causes excessive grinding of the knuckles providing in a short time much lost motion which increases the grinding action on the knuckles in proportion to the lost motion. Furthermore, when the knuckles have relative lateral movement it often occurs that the knuckles are engaged only at the ends or at the maximum distance from the fulcrum point with the result that instead of exerting the pulling strain in a direct line with the drawbars, a great strain is exerted on the knuckles causing breakage thereof. This is due to the fact that when the knuckles engage only at the tips or ends a much greater leverage is obtained and consequently an enormous strain is brought on the pivot for the knuckles and the knuckles themselves.

Another objection to drawheads and couplers heretofore constructed is that the abutting faces of the drawheads by the continual relative movement causes excessive wear when the drawheads are first used, until the faces are worn smooth, and after that the wear does not seem to be noticeable. However in wearing the faces smooth considerable play or lost motion is provided which heretofore could not be compensated for and rendered the drawheads and couplers permanently unsatisfactory.

It is an important object of this invention to provide guides and locking faces or members on the drawheads by means of which the knuckles are guided and automatically forced together and locked when completely coupled so that not the slightest relative movement can occur between the knuckles and thereby preventing wear on the meeting faces of the knuckles and uneven wear on the ends of the knuckles.

It is further an important object of this invention to provide drawheads and couplers in which the abutting faces are smooth plates of steel to prevent the excessive wear which occurs on drawheads of the ordinary type and to provide a construction in which all wear can be compensated for or taken up by insertion of fillers or new wear plates.

It is further a very important object of this invention to provide drawheads in which a recess is provided in the abutting face of each to receive an opposite projection

on the opposite drawhead, said construction being such that free vertical movement of the drawheads is permitted, but in which relative swinging movement between the 5 drawheads is positively prohibited and also relative lateral movement of the drawheads.

It is also an object of this invention to afford drawheads adapted for use either on interurban electric cars or on rolling 10 stock for steam roads, as preferred, and also to provide a construction adapted for use on interurban roads but adapted also to couple with standard M. C. B. draft gear used on steam roads without the necessity of 15 change, addition or removal of parts.

It is also an object of the invention to afford a construction which, when used for interurban service, insures the draft gears at all times remaining in alignment while 20 permitting the cars to follow readily about any curves that may exist in the road and without bringing any strain upon the draft gear because of such curvatures.

It is also an object of the invention to 25 afford a construction in which the wear in any part of the drawhead may be quickly taken up and in which wear is to a large extent obviated.

The invention consists in the matters 30 hereinafter described and more fully pointed out and defined in the appended claims.

In the drawings: Figure 1 is a top plan view of two drawheads embodying my invention, showing the same coupled. Fig. 35 2 is a side elevation thereof. Fig. 3 is an enlarged fragmentary top plan view showing the drawheads in the act of coupling. Fig. 4 is a similar view with parts in section showing the drawheads coupled. Fig. 40 5 is an enlarged transverse section taken at the knuckle pivot pin, but showing the latter in elevation. Fig. 6 is an enlarged top plan view of the knuckle. Fig. 7 is an enlarged fragmentary sectional detail of the 45 tail of the knuckle showing the reinforcement thereon against wear. Figs. 8, 9 and 10, are slight modifications of the construction shown in Fig. 2.

50 As shown in the drawings: 1, indicates the drawhead, which in the present instance is shown for convenience in connection with a draft gear 2, of a familiar type, and such as set forth in a prior patent issue to me, 55 and frequently used for interurban and street cars in connection with a radius bar, 3, which extends back to, or nearly to the bolster of the car to carry the draft to the center of support. When so used, the draw- 60 head and outer end of the radius bar slide laterally on a carrying iron 4. The drawhead, as shown, is of the M. C. B. type and is provided with a pivotally supported knuckle 5, as is usual, the tail 6, of which 65 extends into the drawhead and is adapted

to be engaged and locked by a locking pin or bolt 7, any of the well known constructions for this purpose may be made to answer.

Extending laterally from the drawhead 70 and integral therewith and at the back of the knuckle is an extension 8, affording a recessed seat, the back of which is substantially at a right angle with the longitudinal axis of the draft gear and in the back 75 of which is removably secured a filling plate 9, by means of rivets, bolts or any suitable attaching means. As shown, the extension 8, extends above and below the drawhead proper and is provided at its top and at 80 its bottom with flanged top and bottom walls 10 and 11, as shown in Figs. 2 and 5. As shown, the top wall or flange 10, presents a flat face on its under side while the bottom flange is inclined slightly or is 85 flat for a short distance from the web 8, and is then inclined downwardly to act as a guide should it be necessary. Of course, it is to be distinctly understood that both the top and bottom flanges may be directed 90 at right angles with the web or wall 8, as shown in Fig. 8, or both may be inclined as shown in Fig. 9 and that the distance between the same may be varied to suit any requirement.

The opposite side or jaw of the drawhead is extended to afford a projection 12, adapted to fit into the recess on the complementary drawhead, as shown in Fig. 4, and as shown, is provided also with a plate 13, removably 100 but rigidly secured thereto by screws, bolts, rivets or otherwise, said plate 13, bearing firmly against the plate 9, when the drawheads are coupled in the recess in the extension 8.

105 Integral with each drawhead is a curved guiding and locking plate, flange or extension 20, against which the projection 12, engages in coupling which gradually forces the knuckles together and when the drawheads are coupled lock the knuckles from relative lateral or transverse movement.

The knuckle 5, is shaped as is usual with knuckles of the class described and on the tail 6, thereof is fitted a plate or shell 14, 115 of steel, which is riveted thereto and which engages behind the locking pin 15, as shown in Fig. 5, in coupling.

In the construction shown I have for convenience illustrated a simple form of automatic coupler in which a substantially rectangular locking pin is provided with a recess therein at a point normally below the knuckle but which, when the locking pin is elevated, permits the knuckle to swing clear 125 and also in which said locking pin is provided at the upper side of said recess with an inclined face 16, so that in coupling the tail of the knuckle engages beneath the same to lift the pin. I have also shown a lever 17, 130

5 pivoted on a bracket 18, at the lower side of the coupler and one arm 19, of which extends beneath the end of the locking bolt or pin so that when the lever 17, is drawn outwardly the arm 19, acts to lift the locking pin sufficiently to permit the knuckle to swing to open position, thus uncoupling the drawheads.

10 The operation is as follows: The drawheads having been fitted with plates both on the projections 12, and on the extensions 8, and preferably also upon the tail of the knuckle, as before described, are adjusted so that when in coupled relation there is 15 practically no lost motion, said interfitting projections on the sides of the drawheads affording together with the engaging knuckles 5, substantially alined engaging points, the center of which or the knuckles 20 serve only for traction while the laterally engaging faces serve for buffing and also holding the draft gears of the cars when coupled in strict alinement, although owing to the vertical length of the extension 8, as 25 compared with the narrow projection 12, as shown in Fig. 2, great amplitude of relative vertical movement is permitted. Furthermore, where such draft gears are carried 30 upon radius bars as frequently occurs, the extending point of the jaw and the complementary recesses in the lateral projection on the complementary head serve to bring said drawheads in alinement when the drawheads are 35 brought together in this way facilitating coupling and when once coupled, affording a very positive and rigid connection. Obviously, such drawheads couple readily with any drawhead of the M. C. B. type. The prior 40 existing types of such drawheads lacking such lateral projections couple readily, and when coupled, may be operated as heretofore. Wear will not occur until after a considerable period of use, if then, inasmuch as all 45 wearing surfaces are hardened steel. When wear does occur, however, the wear plates may be replaced with thicker ones or released and a thin filler plate or sheet of metal may be inserted behind the same, in this way enabling the operator at a very trifling expense in time and trouble, to 50 maintain the draft gear at maximum efficiency so far as wear is concerned, for long

periods of time. It is further seen that when the knuckles are coupled, owing to the projections bearing against the inner ends 55 of the guide and locking members 20, that the knuckles are locked from relative lateral or transverse movement and friction and wear on the meeting faces of the knuckles is eliminated. Furthermore, these guiding 60 members tend to force the knuckles into engagement and act to guide the parts while coupling.

Of course, I am aware that any of the ordinary locking mechanisms heretofore 65 used for M. C. B. couplers may be employed and I have shown a particular type of locking bolt only for convenience of illustration. I am aware also that other means may be employed to insure the rigid alinement 70 of the draft gear to couple the cars without departing from the principles of this invention and I have attempted to show but one of several possible constructions. I therefore do not purpose limiting the patent to be issued upon this application otherwise than necessitated by the prior art.

I claim as my invention:

1. A drawhead of the class described embracing in connection with the pivoted 80 knuckle, a projection on one side of the drawhead and a recess on the opposite side of the drawhead formed by an inner curved guide wall located to the rear of said knuckle and integral with said draw head, 85 upper and lower walls, and a flat base wall.

2. In a device of the class described drawheads each having a vertical recess therein formed by a curved inner side wall, an upper wall, an inclined lower wall, and a 90 back wall having a plate removably secured thereto, and a projection integral with each drawhead of less width than the recess adapted to permit free vertical movement when the drawheads are coupled, and prevent lateral swinging of the drawheads. 95

In testimony whereof I have hereunto subscribed my name in the presence of two subscribing witnesses.

WILLIAM T. VAN DORN.
